No. 854,226.

PATENTED MAY 21, 1907.

H. B. LEVY.
FOUNTAIN PEN.
APPLICATION FILED JULY 13, 1906.

UNITED STATES PATENT OFFICE.

HENRY B. LEVY, OF NEW YORK, N. Y.

FOUNTAIN-PEN.

No. 854,226.

Specification of Letters Patent.

Patented May 21, 1907.

Application filed July 13, 1906. Serial No. 326,060.

To all whom it may concern:

Be it known that I, HENRY B. LEVY, a citizen of the United States, residing at New York city, Manhattan borough, county and State of New York, have invented certain new and useful Improvements in Fountain-Pens, of which the following is a clear, full, and exact description.

This invention relates to that class of fountain-pens known as "self-fillers," and has for its object to provide a fountain-pen of this character of great simplicity and hence at little expense and which will at the same time perform the functions required in pens of this class in an effective manner.

To these and other ends which will herein-after appear, the invention comprises the novel features of improvement and combination and arrangement of parts which I will now proceed to describe and finally claim, reference being had to the accompanying drawing, forming part hereof, wherein—

Figure 1 is a side elevation of a fountain-pen embodying my improvements, the barrel being shown in section; Fig. 2 is a cross-section thereof, the section being taken on a line *a—a* in Fig. 1; Fig. 3 is an enlarged plan view of the compressor-shoe and support therefor; and Fig. 4 is a longitudinal section of the compressor-shoe support, the section being taken on a line *b—b* in Fig. 3.

Like numerals of reference indicate corresponding parts in the several views.

In the accompanying drawing, the numeral 1 indicates the barrel of my improved fountain pen, and 2 is the nozzle-section thereof frictionally held in one end of the barrel, as at 3, the nozzle being provided with the usual pen and feeder-bar 4 and 5, respectively. The nozzle-section 2 has a reduced portion 6 adapted for frictional contact in the barrel, so as to be readily removable therefrom. Into the reduced portion 6 a removable nipple 7 is inserted, and to this nipple is attached a compressible reservoir 8, preferably made of rubber. Within the barrel 1, I provide a movable compressing-shoe 9 which is adapted to rest upon the reservoir 8. Said shoe is movably supported within the barrel by a support 10, preferably comprising two sectors 10 $\frac{1}{2}$, 10 $\frac{1}{2}$ joined by a transverse bar 11, as shown in Fig. 3, said support 10 being adapted to be sprung into and frictionally held in the barrel 1. The shoe 9 is provided with a slot 9' to permit the shoe to freely pass over or along the transverse-bar 11, whereby

said shoe 9 may readily move transversely of the barrel when pressure is applied thereto. The upper end of the barrel is provided with a removable plug 13, which has a reduced portion 14 adapted for insertion into said end of the barrel, and to be frictionally held therein so as to be readily detached. From the reduced portion 14 a stud or the like 15 extends, the purpose of which will be presently described. The wall of the barrel is provided with an opening 12, to permit of the manipulation of the shoe 9.

To fill the sac or reservoir of my improved pen, the plug 13 is removed from the end of the barrel and the stud 15 thereof inserted into the barrel and pressed against the shoe 9 through the opening 12, as shown by dotted lines *a* in Fig. 1. This compression extends practically along the entire length of the reservoir, as shown by dotted lines *B* in Fig. 1, the hereinbefore described manner of supporting the shoe 9 permitting of the entire body of the shoe to be pressed against the reservoir, and thus producing a complete or practically complete expulsion of air. When the plug 13 is withdrawn, the inflation of the reservoir will cause the ink to flow therein, in well known manner, it being of course understood that the pen is at such time dipped into an ink supply.

It will be observed that when the pen is placed into the pocket and should the ink-reservoir leak, any ink flowing therefrom will be confined within the barrel by the plug 13, at least so far as the opening 12.

Having now described my invention, what I claim and desire to secure by Letters Patent is:

1. A fountain-pen comprising a barrel, a compressible ink-reservoir within the same, a compressing-shoe movably supported within said barrel, said support comprising sectors connected by a transverse-bar, said bar supporting the said shoe, and means for actuating the shoe.

2. A fountain-pen comprising a barrel, a compressible ink-reservoir within the same, sectors connected by a transverse-bar within said barrel, a compressing-shoe provided with a slot to permit the shoe to freely pass over or along the transverse-bar, and means for actuating the shoe.

3. In combination, a fountain-pen barrel, a compressible sac therein, a compressing-shoe movably supported in said barrel, a support for said shoe provided with means

- adapted to be sprung into and frictionally held in said barrel, said shoe being movably connected at one end to said support, and means for actuating said shoe.
- 5 4. In a fountain-pen, the combination of a barrel, a nozzle-section in one end thereof, a nipple removably held in the nozzle-section, a compressible ink-sac connected to said nipple, a detachable closure in the opposite end 10 of the barrel, said closure having a stud on its forward end, an elongated compressing shoe in said barrel, and a support sprung into and frictionally held in said barrel, to which support said shoe is movably connected, said stud being adapted to impart to said shoe a transverse bodily movement. 15
- Signed at New York, N. Y. this 12th day of July, 1906.

HENRY B. LEVY.
